MASCARA CASE

Isaac S. Beck, Brooklyn, N. Y.

Application May 25, 1933. Serial No. 672,828

1 Claim. (Cl. 132—79)

This invention relates to a container for a cake of mascara or the like and a suitable applicator brush. The principal object of the invention is to provide such a container which shall be compact, easily carried, readily and conveniently used, and of such character as to permit a refill of mascara or the like to be inserted. A further object of the invention is to provide such a case which shall be pleasing in appearance, simple in construction, and inexpensive to manufacture.

In accordance with the invention the improved container is formed as an open-ended case in which a carrier for the mascara cake is slidably mounted and in which the applicator brush may rest. The open-ended case may be closed by a unitary cap of complementary size and shape which may readily be slipped thereover and retained in place by friction. The invention will be described in greater detail in connection with the embodiment illustrated in the accompanying drawing by way of example and in which:

Figure 1 is a view in side elevation of the improved case, one wall being partly broken away in the interest of clearness.

Figure 2 is a view in transverse section through the cap taken on the plane indicated by the line 2—2 of Figure 1 and looking in the direction of the arrows.

Figure 3 is a view in plan of the improved case, the cap being shown as removed and part of the top wall of the case being broken away in the interest of clearness.

Figure 4 is a view in vertical section through the case illustrated in Figure 3 and taken on the plane indicated by the line 4—4 thereof.

Figure 5 is a view in transverse section through the case shown in Figure 4 and taken on the plane indicated by the line 5—5 thereof.

Figure 6 is a view similar generally to Figure 4 but showing the carrier for the cake of mascara fully withdrawn in position for use, the dotted lines indicating the position of the carrier when it is to be removed from the case.

The case *a* is preferably formed from metal in one piece and has an open-end. The side walls of the case are crimped to provide two opposed longitudinally extending ribs *a'* which present themselves interiorly of the case and extend for a greater or less distance. These opposed ribs *a'* constitute ways on which rest slidably a carrier *b* in which is supported a cake of mascara *c*. In the top wall of the case *a* near the open-end thereof are two downwardly extending lugs *a*² which may conveniently be

formed by punching out the metal. These lugs constitute stops which limit the outward travel of the carrier *b* along the ribs *a'*. When the carrier is fully withdrawn, as illustrated in Figure 6, its rear wall will engage the lugs *a*² and further movement of the carrier will thereby be arrested positively.

The ribs *a'* are so spaced with respect to the bottom wall of the case *a* as to permit the ready insertion and removal of an applicator brush *d*, the handle of which protrudes beyond the open-end of the case *a* so that it may readily be grasped. It is evident that the thickness of the case may be determined by the thickness of the cake of mascara desired and the width of the handle of the applicator brush. Similarly, the width of the case will depend on the desired width of the mascara cake. The relationship of elements obviously permits the case to be formed as a very compact unit which may be carried in a hand bag and yet handled with facility. With the carrier *b* and the brush *d* nested in the case as illustrated in Figure 4 the case may be closed by a suitable cap *e* which is similar in shape to the case and of such interior dimensions as to permit it to be slid thereon with a nice fit. Such closure will protect the contents of the case entirely against foreign matter. If desired, the cap may be retained in place more effectively by forming a dimple *a*³ in one wall of the case so as to engage the cap frictionally.

Largely for appearance the case illustrated has at its closed end a false cap *f* which fits snugly thereover and may be frictionally retained by dimples *a*⁴ in the walls of the case which engage the said false cap. The thickness of this false cap and its relation to the case is such that it will present a shoulder to the closure cap *e* and be in alignment therewith when the cap is in position.

The improved construction permits the ready insertion of refill cakes of mascara when required. As shown in Figure 6 the rear wall of the carrier *b* may be inclined with relationship to the bottom wall of the carrier to facilitate a rocking movement on the supporting ribs *a'*. When the carrier is fully withdrawn from the case with the rear wall in contact with the lugs *a*² the outer end of the carrier may be moved upwardly so as to rock the rear wall until its free edge is disengaged from the lugs *a*² after which the carrier may be withdrawn entirely from the case. A carrier with a fresh cake of mascara may be readily inserted by the reverse operation, as will be evident.

Changes in form and arrangement may be made

by one skilled in the art while retaining the novel characteristics described, without departing from the appended claim.

I claim as my invention:

3 As an article of manufacture a unitary metal case for the purpose set forth having side walls and an end wall, the opposite end being open, interior ribs formed by crimping in the opposite side walls along the median line thereof and extending longitudinally of the case, a carrier slid-

ably supported upon said ribs and occupying the space above said ribs, said carrier having a curved end wall, inwardly extending lugs carried by the case and engageable with said curved end wall of the carrier to limit the outward movement of the carrier, said ribs and lugs being so related to the carrier as to permit rocking of the carrier on the ribs to disengage the curved end wall from said lugs, and a cap for the open end of the case.
